(57) **CLAIM**

The ornamental design for an exercise platform with attachable stackable block, as shown and described.

DESCRIPTION

FIG. 1 is an isometric view of the exercise platform with attachable stackable block showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom view thereof;

FIG. 8 is an exploded isometric view of the exercise platform with attachable stackable block thereof;

FIG. 9 is an exploded front elevation view thereof;

FIG. 10 is an exploded rear elevation view thereof;

FIG. 11 is an exploded left side elevation view thereof;

FIG. 12 is an exploded plan view thereof;

FIG. 13 is an exploded top plan view thereof; and,

FIG. 14 is an exploded bottom view thereof.

The broken dash lines in the figures are for illustrative purposes only and represent non-claimed environmental structure. Neither the portions of the environmental structure shown in broken dash line nor the broken dash lines themselves form any part of the claimed invention.

1 Claim, 10 Drawing Sheets
